UNITED STATES PATENT OFFICE.

FRANZ GUILLEAUME, OF BONN, GERMANY.

DESIGN FOR A VASE OR SIMILAR ARTICLE.

SPECIFICATION forming part of Design No. 21,494, dated April 19, 1892.

Application filed March 28, 1892. Serial No. 426,827. Term of patent 3½ years.

To all whom it may concern:

Be it known that I, FRANZ GUILLEAUME, a subject of the Emperor of Germany, residing at Bonn, in the Empire of Germany, have invented certain new and useful Improvements in Designs for Vases; and I do declare the following to be a full, clear, and exact description of the invention, such as will enable others skilled in the art to which it appertains to make and use the same, reference being had to the accompanying drawing, and to the letters of reference marked thereon, which forms a part of this specification.

The distinguishing characteristics of my design are shown in the accompanying drawing, in which the vase proper is represented by the reference-letter *a*. *b* represents a top, and *c* diametrically-opposite handles, which extend down the sides of the vase. These handles are gilded, as usual, and the upper portion comprises an inturned volute scroll *d*, on the upper outer edge of which are formed beads or serrations *e*. Dots *f* are also formed on the sides of the scroll. The lower portion *25* of the handle, which is situated immediately

beneath the scroll, consists of the representation of a leaf *g*, which terminates in an out-turned small scroll *h*. Continuing below this scroll is a succession of overlapping leaves *i*.

The particular portion of the present design, which forms the subject of my present application, consists in the floral decorations, which comprise a stem *k*, from which branches the leaves *i*. In the center of these branching leaves is a group of flowers *m*. Out of the body of these spring stems *n*, bearing flowers *o*. There are also flowers *p* at the base of the stem *k*.

Having thus described my design, what I claim as new, and desire to secure by Letters 40 Patent, is—

The design for a vase or similar article, substantially as herein shown and described.

In testimony whereof I affix my signature in presence of two witnesses.

FRANZ GUILLEAUME.
